INVENTOR
John E. Springer
BY John A. Fraismith
ATTORNEY

UNITED STATES PATENT OFFICE.

JOHN E. SPRINGER, OF PALO ALTO, CALIFORNIA.

COLLAPSIBLE FURNITURE.

1,369,944.

Specification of Letters Patent. Patented Mar. 1, 1921.

Application filed August 5, 1920. Serial No. 401,403.

To all whom it may concern:

Be it known that I, JOHN E. SPRINGER, a citizen of the United States, and resident of Palo Alto, in the county of Santa Clara and State of California, have invented certain new and useful Improvements in Collapsible Furniture, of which the following is a specification.

My invention relates particularly to folding camp furniture, and it is the object of my invention to provide a folding structure that is capable of being collapsed into small space, that will be economical to manufacture, light in weight, and that will be strong, durable and substantially rigid when set up for use. A further object of my invention is to provide a frame forming a part of a structure or capable of independent use that will have the characteristics hereinbefore set forth.

In the drawing:

Figure 1 is a side elevation of a camp stool embodying my invention.

Fig. 2 is a front elevation of the same.

Fig. 3 is a perspective view of the same with the top thereof indicated in dotted lines.

Fig. 4 is a plan view of the frame of the stool in a collapsed condition.

Fig. 5 is a detail section illustrating the method of mounting the several rods on the stool frame.

Referring more particularly to the drawing, 1-1 and 2-2 indicate the legs of the stool, the adjacent legs 1 and 2 being pivoted together at their central points as shown at 3. The upper ends of legs 1 are provided with pins 4 and the upper ends of legs 2 are provided with pins 5. A bar 6 is fitted on pins 4 as shown and a bar 7 is fitted on pins 5 as shown. At 8-8 are a pair of tie rods pivotally mounted in the upper portions of legs 2-2 and engaging orifices 9-9 in the adjacent ends of bar 7.

In each case where a rod is referred to as being pivotally mounted, the pivotally mounted end is bent at an angle to the main portion of the rod as indicated at 10 in Fig. 5, the end being then thrust through an orifice as 11 in the member upon which it is mounted and then riveted as at 12 over a washer as 13.

At 14 is shown the body member of a spider having a pair of rods 15-15 pivotally mounted in its lower end and two pairs of rods as 16-16 and 17-17 pivotally

mounted in its upper end as shown. The rods 15-15 are pivotally mounted upon the lower ends of legs 1-1 and the rods 16-16 are of the same length as rods 15-15 and are pivotally mounted upon legs 1-1 at a point above the intersection of legs 2-2 therewith. The rods 17-17 are bent outwardly at their free ends as at 18-18 to engage orifices 19-19 in the inner surface of bar 6 on either side of the median line thereof. Mounted upon and connecting bars 6 and 7 is a suitable canvas seat portion as shown at 20.

In its collapsed condition the frame assumes the position shown in Fig. 4. In setting the frame up the pairs of legs are extended laterally a distance and bar 7 fitted on to pins 5-5 on legs 2-2, the rods 8-8 being inserted in orifices 9-9 thereby laterally spacing legs 2-2 and bracing the same with respect to bar 7. Bar 6 is now fitted on to pins 4-4 on legs 1-1 thereby spacing the said legs, the seat 20 permitting the folding of legs 2-2 on legs 1-1 but effectually determining the position of each leg 2 with relation to its corresponding leg 1 when extended as shown in figures 1 and 3. The ends 18-18 of rods 17-17 are now inserted in orifices 19-19 in bar 6.

Member 14 is now effectually held in a fixed position with relation to bar 6, and to legs 1-1 through the medium of rods 15-16 and 16-16, thereby thoroughly bracing and supporting the several members against lateral movement. The structure is collapsed by removing bars 6 and 7 and folding the several members and rods as shown in Fig. 4.

Considerable economy is effected in this construction since it eliminates the necessity of using dies in forming special parts and it permits the use of the cheaper and lighter woods.

It is to be understood that the embodiment shown is illustrative only and is in no way to be construed as limiting the scope of the invention as set forth in the following claims.

I claim:

1. The combination with a pair of side members and an end member of a central member spaced a distance therefrom, a pair of bracing elements connecting said central member with each of said side members, and a pair of elements connecting one end of said central member with said end member

at points spaced a distance on each side of the median line thereof.

2. The combination of a pair of spaced side members, an end member removably mounted thereon, a central member spaced from said side and end members, a pair of bracing members connecting said central member and each of said side members, and a pair of elements mounted on one end of 10 said central member and detachably connected to said end member at points spaced a distance on each side of the median line thereof.

3. The combination of a pair of spaced side members, an end member removably mounted thereon, a central member spaced from said side and end members, a pair of bracing members pivotally connected to said central member and each of said side 15 members, and a pair of elements mounted on one end of said central member and detachably connected to said end member at points spaced a distance on each side of the median line thereof.

20 4. The combination of a pair of spaced side members, an end member removably mounted thereon, a central member spaced from said side and end members, a pair of bracing members pivotally connected to said central member and each of said side members, and a pair of elements pivotally mounted on one end of said central member and detachably connected to said end member at points spaced a distance on each side 25 of the median line thereof.

30 5. The combination of a pair of spaced side members, an end member removably

mounted thereon, a central member spaced from said side and end members, and parallelly disposed with relation to said side 40 members, a bracing member pivotally connected to one end of said central member and the free end of each side member, a second bracing member having the same length as said first mentioned bracing members 45 pivotally connected to the other end of said central member and to each side member at a point adjacent the center thereof, and a pair of elements pivotally connected to the last mentioned end of said central member and detachably connected to said end member at points spaced a distance on each side of the median line thereof.

6. The combination of a pair of spaced side members, an end member removably mounted thereon, a central member spaced from said side and end members, a pair of bracing members connecting said central member and each of said side members, a pair of elements mounted on one end of 50 said central member and detachably connected to said end member at points spaced a distance on each side of the median line thereof. 55

5. The combination of a pair of spaced side members, an end member removably mounted thereon, a central member spaced from said side and end members, a pair of bracing members connecting said central member and each of said side members, a pair of elements mounted on one end of 60 said central member and detachably connected to said end member at points spaced a distance on each side of the median line thereof. 65

6. The combination of a pair of spaced side members, an end member removably mounted thereon, a central member spaced from said side and end members, a pair of bracing members connecting said central member and each of said side members, a pair of elements mounted on one end of 70 said central member and detachably connected to said end member at points spaced a distance on each side of the median line thereof. 75

JOHN E. SPRINGER.
